UNITED STATES PATENT OFFICE.

HORACE K. JONES, OF HARTFORD, ASSIGNOR TO THE RUSSELL & ERWIN MANUFACTURING COMPANY, OF NEW BRITAIN, CONNECTICUT.

METAL-SCREW MACHINE.

SPECIFICATION forming part of Letters Patent No. 252,949, dated January 31, 1882.

Application filed June 29, 1881. (Model.)

To all whom it may concern:

Be it known that I, HORACE K. JONES, of the city and county of Hartford, and State of Connecticut, have invented certain new and useful Improvements in Metal-Screw Machines; and I do hereby declare that the following specification, taken in connection with the accompanying drawings, forming a part of the same, is a full, clear, and exact description thereof.

My invention relates to mechanism for pointing metal-screw blanks and to mechanism for threading the shanks thereof.

My improvements consist, first, in a novel combination of a revolving jaw-spindle, threading-dies, and a vibrating centering and pointing tool with mechanism which places said tool into and away from the plane of the axis of the jaw-spindle and advances and retires said tool in the same plane; second, in mechanism for threading the shanks of the blanks, which consists of the following elements: a threading-die in two parts, which, when acting upon the blank, are supported and held so as to have the practical advantage of the accurate cut of a solid die, but which, when the blank has been threaded, are separated or opened and promptly retreated without the loss of time incident to the running off of a solid die, a carriage upon which the two part threading-die is mounted, and which moves the die up to its work, but has a partial rearward movement independent of said die, devices located on the carriage and connected with the die, which, when the carriage moves rearward after the die has performed its work, will close the parts of the die, and mechanism for operating the carriage; third, devices located on the carriage which are capable of quickly and accurately adjusting the two parts of the die to each other, so that the gage of thread cut by the die will be determined, and can be maintained when the die becomes slightly worn.

Referring to the drawings, Figure 1 represents a plan of a portion of a machine in which all my improvements are embodied, the time being taken after the blank has been pointed and while the dies are advancing. Fig. 2 shows a vertical section of the same on line *xx*. Fig.

3 represents the positions of certain parts of the mechanism when the two parts of the threading-die are about to be closed, and Figs. 4 and 5 show details of construction.

A is a portion of the frame of the machine, 55 upon which a continuously-revolving jaw-spindle, B, of any preferred construction is mounted. In this spindle the blanks are clamped in the usual manner while being operated upon, the blanks being supplied to the spindle by the 60 usual feeding mechanism.

C is the cam-shaft of the machine, which is continuously driven from the spindle by means of a pinion, *b*, secured to the spindle, an intermediate gear, *b'*, and a gear, *c*, secured to the 65 shaft, as shown in Fig. 1, or by equivalent means.

D is the pointing tool, which is in the form of an arm, and is secured to a rock-shaft, E, capable of a sliding movement. This tool has 70 a perforation which is preferably supplied with a bushing, *d*, Fig. 2, of the requisite size to receive the ends of the blanks and support them during the pointing operation.

Mounted in the tool D is a cutter, *D'*, which 75 is clamped therein by a screw, *d'*, and occupies a plane in the rear of the blank-supporting portion of the tool, as shown in Fig. 2. Attached to the tool D and to the frame of the machine is a spring, *D*², or equivalent device, 80 which tends to move the tool upward and toward the jaw-spindle, thereby rocking the shaft E, and moving it longitudinally. The action of this spring and the motions of the tool are governed through a lever, *E'*, secured 85 to the rock-shaft E by cams *F* *F'*, located on the shaft C, the spring *D*² holding said lever in engagement with the cams. The cam *F* is provided with a declining face, *f*, a depression, *f'*, and a rising face, *f*², the face *f* and depression *f'* allowing the spring to move the tool upward, thereby bringing the bushing *d* into alignment with the blank, and the face *f*² moving the tool downward to the position shown in Figs. 1 and 2. For allowing the 95 spring to bring the tool into engagement with the blank, after it has been aligned the cam *F'* is provided with a depression, *f*³, and for moving the tool rearward and out of engagement with the blank, after it has performed 100

its work the said cam is supplied with a rising face, f^4 , as shown in Fig. 1.

The operation of the pointing mechanism is as follows: A blank having been clamped in the jaw-spindle, the face f and depression f' of cam F allow the spring D^2 to depress the lever E' and move the tool upward to bring the bushing d into alignment, the alignment being maintained by a set-screw, d^2 , Fig. 2, upon the tool D, or by the periphery of the depression f' on the cam. The depression f^3 in the cam F' now allows the spring to move the tool and lever E' longitudinally and bring the cutter into and maintain its engagement with the blank whose end is supported during the pointing operation by the bushing d . The pointing being completed, the face f^4 on the cam F' moves the lever E' and tool D rearward. When the tool has cleared the blank the face f^2 on the cam F elevates the lever E' and depresses the tool D to its original position. Although but one cutter, D', is shown, yet any desired number may be employed; or the cutter may be in the form of a burring or milling instrument.

Although, as shown and described, the pointing-tool is moved both in vertical and horizontal planes, yet if the pointing of the blanks is unaccompanied by a threading of the same, the tool need move only longitudinally to and fro from the jaw-spindle.

I am aware that devices have heretofore been employed for centering and pointing blanks in screw-cutting machines—as, for instance, in machines wherein the threading operation is performed by a chaser, the pointing-tool occupies and is advanced to and withdrawn from the blank in the line of the axis of the revolving blank-holder; but such a pointing-tool cannot be used in a machine wherein open dies move to and from a blank-holder in the same plane. Also, in machines wherein dies are moved to and from the revolving blank-holder in the same plane therewith, a pointing-tool has been employed which moved to and from the plane occupied by the blank in its revolving holder in a circular path at right angles to the axis of the holder; but in this prior organization the pointing-tool and dies occupied an axially mounted holder common to both, so that the dies and pointer were moved to and fro in the same arc of a circle; but this necessitated a movement of the dies other than was requisite for their actual operation, which involved more or less liability of their failure to always occupy the same exact position relatively with the prolongation of the axial line of the jaw-holder. Also, in machines for shaving and pointing, the pointing-tool has been located within the blank-holding jaws, which precluded the threading operation in the same machine. Also, in machines wherein no pointing is done, but wherein dies and jaws are employed in the same plane, a centering device has been employed which swung upward from below; but with such a centering device no cutter could be employed for pointing, because the centering-tumbler

moving in the arc of a circle, could not apply the cutter to the blank in a line corresponding to the axis of the blank. In my machine the dies and jaws occupy the same plane and neither departs therefrom, and therefore their actual coincidence is always assured, and while this in itself is not new it is novel to combine therewith a centering and pointing tool which of necessity must have the novel movements imparted to it as by me—viz., the upward swing, the advance upon the blank, the rearward movement to disengage from the blank, and the dropping movement to retire from the path of the advancing dies.

The advancing of the pointer to the blank in the plane thereof by a spring, acting also so that the pointing work is performed under a yielding or spring pressure, is not a novel feature in itself; but the organization, with a pointer, of a spring which not only thus advances the pointing-tool in a plane with the blank, but also brings said pointer coincident with the blank, is a novel and valuable feature, because of its efficient promptness in operation.

The threading of the blanks is performed by dies G G, each of which is mounted in a holder, G', having its rear portion bifurcated, as shown in Fig. 5. The die-holders G' G' are mounted on a carriage, H, which has longitudinal forward and rearward movements imparted to it by cams J K, respectively, located on the cam-shaft C. These cams during their revolution engage a roller, l, upon a lever, L, which lever is pivoted at its outer end to the frame of the machine, and has a forked inner end, which engages a pin, h, upon the carriage, and thereby controls its movements, the carriage sliding in guides H' upon the frame. The rear ends of the die-holders G' are pivoted together by a pin, g, which passes through a slot, h', in the carriage. The pin g also passes through a link, M, which is connected at its rear end to a lever, N, pivoted to the carriage, the outer end of the said lever projecting beyond the carriage, so that it may engage a block, O, located on the frame, as shown in Figs. 1, 2, and 3. As shown in Figs. 3 and 5, the outer ends of the die-holders have flat sides g' and inclined portions g'' , and, as shown in Figs. 1 and 3, a spring, g^3 , is located between said holders, the said spring tending to open the dies.

When the dies are closed, as shown in Fig. 1, they are retained in such condition by right and left hand screws P P', which are mounted in the end of the carriage H and engage the flat sides g' g'' of the die-holders. The heads of these screws are in the form of gears, which are engaged by pinions $r r$ on a shaft, R, passing through the carriage, one end of said shaft being squared or otherwise formed, so that it may be rotated. By means of the shaft R the distance apart of the outer ends of the die-holders G' G', and consequently the distance apart of the dies G G, is regulated, for by turning the shaft R the screws P P' are turned in or

out, and the dies are made to approach or re-cede from each other. The pinion-shaft R and the gear-headed screws P P' therefore afford a ready means for accurately adjusting the gage 5 of the thread which the dies shall cut.

Open dies mounted in pivoted jaws have heretofore been rendered adjustable by means of wedge-blocks controlled by a worm and screw; but my adjusting-screws, controlled by 10 the shaft and pinions, are much simpler and fully as effective and reliable.

The leading cam J is of peculiar construction, as shown in Figs. 1 and 4, in that it has an adjustable face, J', which is provided with 15 a quick rise, j, and a slow rise, j'. The rise j acts upon the lever L to promptly advance the dies to engage the blanks, and the rise j' moves the dies along the blank according to the pitch of the threads to be cut when the engagement 20 is first effected. By having the face J' of the leading cam J adjustable by means of a screw, j², or equivalent, a ready and convenient means is provided for regulating the initial cut of the dies in accordance with the pitch of thread de- 25 sired.

The operation of threading the blank is as follows: The jaw-spindle having been supplied with a blank, and the blank having been pointed—if a pointed blank is desired—the lever- 30 roller l is engaged by the portion j of the leading-cam face J'; and the carriage H and all the mechanism thereon are promptly advanced toward the blank by the lever L, the pin g engaging the rear end of the slot h'. When the 35 dies G G come into engagement with the blank, the portion j' of the leading-cam face moves the dies along the blank according to the pitch of threads to be cut, the carriage and mechanism thereon moving at the same time and speed. 40 When the thread has been sufficiently started to insure the continued movement of the dies by the lead of the threads the leading cam passes out of engagement with the lever-roller l, and the dies and carriage continue to move 45 forward, being drawn onward by the lead of the thread. Just before the requisite length of thread has been cut the cam K engages the lever-roller l and moves the carriage H rearward. Since the dies are in engagement with 50 the thread and are performing their work, however, they, their holders, and the link M will not partake of this rearward movement until the backward motion of the carriage has caused the ends of the screws P P' to pass off the sides 55 g' g' of the die-holders and allowed the spring g³ to open the dies, and thereby cause them to disengage the blank. When this takes place the relative position of the carriage and parts thereon will be as shown in Fig. 3, the pin g 60 engaging the front end of the slot h', and the outer ends of the lever N being in its rearward position. The dies and other mechanism on the carriage will now partake of its rearward movement until the lever N engages the block O, 65 as shown in Fig. 3. A continued rearward movement of the carriage and parts thereon

will cause the lever N through the link M to retreat the dies at a quicker speed, and bring the screws P P' into engagement with the inclined portions g² g² on the die-holders, over 70 which portions the screws will pass and close the dies to their original position, the screws coming into engagement with the sides g' g' and locking the dies closed, as shown in Fig. 1. The cam K now ceases to engage the lever-roller l, and the carriage and mechanism thereon remain stationary until the jaw-spindle has been supplied with another blank, and the cam J again acts to produce a forward movement of the parts. 80

In prior machines embodying open jaw-dies their release has been effected by advancing the dies beyond their holder by the draft thereon of the thread cut by the dies, thereby permitting said dies to expand for releasing themselves from the screw just cut; but this action is graduated according to the pitch of the thread, whereas in my machine the carriage is promptly thrown backward at the proper moment, securing a promptness of release, which is material in machines where rapidity in operation is 90 an important consideration.

The machine shown in the drawings is adapted both to point and thread screw-blanks; but either operation alone may be performed 95 by it.

If it is desired only to thread the blanks, the spring D² may be detached from the pointing-tool, when the said tool will be inoperative.

The machine may be arranged to point and thread different lengths of blanks by adjusting the position of the pointing-tool upon the rock-shaft, and by a proper arrangement and adjustment of the threading mechanism.

Having described my invention, what I claim, 105 and desire to secure by Letters Patent, is—

1. The combination, substantially as hereinbefore described, with a revolving jaw-spindle for holding screw-blanks, and threading-dies which move to and from said jaws in 110 alignment with the spindle-axis, of the vibrating centering and pointing tool, and the mechanism, substantially as described, for placing said tool into and away from the plane of the axis of the jaw-spindle, and for advancing and 115 retiring said tool in said plane, as set forth.

2. The combination of a revolving jaw-spindle adapted to hold a blank, a pointing-tool, as described, a cam for depressing said tool and moving it rearwardly, and a spring or 120 equivalent for lifting said tool into alignment with the axis of the jaw-spindle and bringing said tool into engagement with the blank, and causing the tool to point the blank under a yielding pressure, substantially as set forth. 125

3. The combination, substantially as described, of a sliding carriage having a pair of threading-dies pivoted thereto, but capable of a longitudinal movement independently of the movement of the carriage, and mechanism, 130 substantially as described, for giving a rearward movement to the carriage just before the

threading of the blank is completed, so as to enable the threading-dies to open and be clear of the threaded blank.

4. The combination, substantially as described, of a sliding carriage having a pair of threading-dies pivoted thereto, but capable of a longitudinal movement independently of the movement of the carriage, suitable mechanism for giving a rearward movement to both the carriage and the threading-dies, and means, as described, for causing the threading-dies to be moved independently of the carriage, so that they may be closed and locked preparatory to the ensuing advancing movement of the carriage to thread the succeeding blank.

5. The combination of a sliding carriage, H, a pair of die-holders, G' G', pivoted thereto, but capable of an independent longitudinal movement thereon, the said holders having a

portion, g', of their sides flat, and a portion, g², recessed and inclined, and adjustable locking-screws P P', substantially as described.

6. In an open-die screw-threading machine, the combination, with the longitudinally-reciprocating die-holders, having wedge-shaped or inclined sides, of right and left hand adjusting-screws, which are advanced and retired for contact with the sides of the die-holders, thereby gaging the approach of said dies toward each other, and a toothed pinion-shaft engaging with toothed heads upon said adjusting-screws for rotating them simultaneously, substantially as set forth.

HORACE K. JONES.
